UNITED STATES PATENT OFFICE.

JOHN HANNEN, OF CHICAGO, ILLINOIS.

SWING.

SPECIFICATION forming part of Letters Patent No. 431,260, dated July 1, 1890.

Application filed November 12, 1889. Serial No. 329,981. (No model.)

To all whom it may concern:

Be it known that I, JOHN HANNEN, of Chicago, in the county of Cook and State of Illinois, have invented a new and Improved 5 Swing, of which the following is a full, clear, and exact description.

My invention relates to that class of swings in which suspension-rods instead of ropes are used; and the object of my invention is 10 to provide a safe and comfortable swing that will occupy but little space and that can be easily operated by the person swinging.

To this end my invention consists in a movable pyramidal frame having two swinging 15 suspension-rods carrying a slightly-tilting spring-seat and attached to said frame near the top.

The details of this construction will be hereinafter fully explained, and more specifically 20 pointed out in the claims.

Reference is to be had to the accompanying drawings, forming a part of this specification, in which similar letters of reference indicate corresponding parts in both the figures.

25 Figure 1 is a front elevation of a swing embodying my invention, and Fig. 2 a side elevation of the same.

The frame A consists of four standards which meet at the top, where they are firmly 30 fastened together by the key a, cross-ties, and bolts. The standards slope outwardly toward the base of the frame, forming the four corners thereof, and at the bottom they are firmly connected by the cross-bars or sills B and B', 35 which constitute the base of the frame.

Upon two opposite sides of the frame A, near the top, are cross-pieces b, which are securely attached to the sides of the frame and provided with ears c, to which is secured the 40 shaft d. The shaft d extends across from one cross-piece b to the other, and from it is suspended the swing proper.

The side pieces or suspension-rods D of the swing are provided at the extreme top with 45 metal plates e, which turn upon the shaft d, and thus cause less wear and friction than would be the case if the wooden rods D were attached directly to the shaft. The plates e are prevented from sliding on the shaft d by 50 the collars e', attached to the shaft on each side of the swing. The side pieces D are securely braced and are fastened together at

the bottom. They are provided with a seat E, which is pivoted to the side pieces D, near the front part of the seat, the back part of 55 the seat being supported by a spring f, one end of which is attached to the seat and the other to the side pieces below the seat. Just below the back part of the seat and attached to each side piece is a rest g, to prevent the 60 seat from falling if the spring f should break. At a convenient distance above the seat the side pieces D are provided with handles h, to be grasped by the person swinging.

One of the standards of the frame A should 65 be provided with cleats i, which serve as a ladder, up which a person may climb to oil the bearings at the top.

To set and keep the swing in motion, the person swinging simply leans backward in the 70 swing. This causes the seat to tip, and by changing the center of gravity imparts a forward movement to the swing. By repeating this action the swing may be kept in motion and forced to any desired height.

Having thus described my invention, what I claim as new, and desire to secure by Letters Patent, is—

1. The combination, with the suspension-rods of a swing, of a seat pivoted near its 80 front edge between and to the said rods, and stops secured to the suspension-rods below the seat and projecting rearwardly to limit the downward movement of the seat, substantially as described.

2. The combination, with the suspension-rods of a swing, of a seat pivoted between the rods at one side of its center, and a spring secured to the rods and to the seat, and a stop secured to each rod below the seat, substantially as herein shown and described.

3. A swing consisting, essentially, of the movable pyramidal frame composed of the standards A and sills B B', the cross-pieces b, attached to said frame, the shaft d, supported 95 upon said cross-pieces, the side pieces D, suspended from said shaft, the pivoted seat E, handles h, spring f, and rest g, all arranged substantially as shown and described.

JOHN HANNEN.
